UNITED STATES PATENT OFFICE.

ALVA OWEN, OF CHICAGO, ILLINOIS.

WIRE-COILING MACHINE.

SPECIFICATION forming part of Letters Patent No. 393,920, dated December 4, 1888.

Application filed September 10, 1888. Serial No. 285,067. (No model.)

To all whom it may concern:

Be it known that I, ALVA OWEN, a citizen of the United States, residing at Chicago, in the county of Cook and State of Illinois, have 5 invented a new and useful Improvement in Wire-Coiling Machines, of which the following is a specification.

My invention relates, generally, to an improved machine for coiling wire; and it relates more particularly to a machine for forming an especial spring which constitutes the blank out of which is produced a certain spring-clamp, which latter I employ in the construction of an electric belt secured to me 15 by Letters Patent of the United States No. 368,546, dated the 16th day of August, 1887.

In the drawings, Figure 1 is a plan view of my improved wire-coiling machine with a blank in position as it appears before the commencement 20 of the coiling operation; Fig. 2, a side elevation of the same, illustrating the relative initial positions of the parts with a blank inserted; Fig. 3, a similar view of the same, showing the relative final positions of the parts and a 25 spring formed from the blank; Fig. 4, a view in elevation of the side of the machine opposite that shown in Figs. 2 and 3, illustrating the initial relative positions of the parts in full lines and their final positions in dotted 30 lines; Figs. 5 and 6, broken perspective views of details, and Fig. 7 a detail view of the spring.

A is the frame of the machine, comprising a base portion, B, provided with screw-holes, 35 through which it may be fastened upon a support carrying standards B' B², which are perforated toward their upper ends to afford bearings for a shaft, C, which latter projects beyond the standards at opposite ends. The 40 shaft C toward one end fits closely the bearings provided in the standard B² and toward its opposite end is screw-threaded, as shown at t, to fit a corresponding thread provided in the bearing of the standard B'. At its end 45 adjacent to the screw-threaded portion t the shaft carries a crank, D.

E is a bed-plate supported vertically on the shaft C, near the end of the latter, beyond the standard B². The plate E is fixed upon the shaft 50 C to rotate with it, and the part of the shaft which projects beyond the bed-plate is reduced

in diameter and shaped in a manner to afford a stud, s, surrounded at the part adjacent to the bed-plate E by a cam-shaped projection, s', as shown in Fig. 5. A guide-plate, r, is rigidly 55 secured to the outer side of the bed-plate in the position shown, and a gage, q, is pivoted at q' to render it adjustable toward and from the stud s, for a purpose hereinafter described, and fastened in its adjusted position by a set-screw, q².

Adjacent to the guide-plate r, and normally in contact therewith, is a clamp, p, on the end o² of a short shaft which passes through the bed-plate E and carries at its opposite end a handle, preferably in the form of a lever, p'. The lever p' rests normally against the shoulder of a guide-clip, p², where it is held by a spring, p³. The clamp p and lever p' are rigid upon their connecting-shaft, so that when the lever 70 p' is raised against the resistance of the spring p³ from its normal position against the shoulder of the guide-clip p² it turns the clamping-edge of the clamp p away from the adjacent edge of the guide-plate r, and when the lever 75 p' is released the spring p³ causes it and the clamp p to return to their normal positions, respectively, against the shoulder of the guide-clip p² and the edge of the guide-plate r.

F is an adjustable and removable holder, 80 provided with a shoulder, o, and an eye, o', toward one end to fit loosely over the stud s.

A stud affording a stop, n, projects from the outer side of the standard B', and a similar stud, also affording a stop, n', projects from 85 the inner side of the bed-plate E, the stops being thus at opposite sides of the frame A. The screw-thread upon the shaft C and correspondingly-threaded bearing in the standard B cause the shaft as it is rotated to travel 90 forward or backward, depending upon the direction of its rotation within the limits afforded by the stops n and n'. The initial position of the bed-plate E is that illustrated in Figs. 1 and 2 and by full lines in Fig. 4 when 95 the crank D is at its nearest approach to the standard B', where it makes contact with the stop n. The final position of the bed-plate (illustrated in Fig. 3 and by dotted lines in Fig. 4) is reached after nearly a turn and a half of the shaft C, when the stop n' comes into contact with the standard B².

The operation of my improved machine to form the spring X' (shown in Fig. 7) from a straight length of wire constituting the blank X is as follows: The clamp *p* is turned out 5 of contact with the guide-plate *r* by raising the lever *p'* and a blank, *X*, inserted between the clamp and guide-plate, with one end against the gage *q*. The lever *p'* is then released, thereby causing the clamp *p* to bind 10 the blank *X* tightly against the guide-plate *r*. The holder *F* is then adjusted upon the stud *s*, with its shoulder *o* resting against the blank *X*. The operator then grasps the holder with one hand to retain it and the free end 15 of the wire *X* in a fixed position, and with the other hand operates the crank *D* to cause the bed-plate *E* to rotate and bend the wire *X* near its middle about the pivot or stud *s* until the stop *n'* reaches the standard *B*³, when 20 the turning is impeded and the operation completed. The holder *F* and spring *X'* (thus formed) are then removed from the bed-plate *E*, and the latter is turned back to its initial position to be ready for another operation. 25 The cam *s'*, (shown in Fig. 5,) though not indispensable, assists in guiding the wire in the formation of the coil. The holder *F*, though it affords convenient means for steadyng the blank during the coiling operation, may, if 30 desired, be dispensed with and the wire held by the fingers of the operator. The spring *X'* constitutes a blank out of which, as before stated, a certain spring-clamp is made, and improved machinery for performing the latter 35 operation forms the subject of a separate concurrent application for Letters Patent which was filed by me on the 2d day of August, 1888, and which bears Serial No. 281,795.

What I claim as new, and desire to secure 40 by Letters Patent, is—

1. In a wire-coiling machine, the combination, with the frame, of a bed-plate, *E*, supported on a rotary shaft, *C*, a stud, *s*, and clamping mechanism, to hold the wire, on 45 one side of the bed-plate, and a spring-lever, *p'*, on the opposite side of the bed-plate connected with the clamping mechanism, substantially as described.

2. A wire-coiling machine comprising, in 50 combination, a frame, *A*, having a base portion, *B*, and standards *B'* and *B*², a rotary longitudinally-reciprocating shaft, *C*, supported in the standards and carrying toward one end a crank, *D*, and toward its opposite 55 end a bed-plate, *E*, a stud, *s*, and clamping mechanism for the wire on one side of the

bed-plate *E*, a stop, *n*, to limit the rotation of the bed-plate *E* in one direction, and a stop, *n'*, to limit its rotation in the opposite direction, substantially as described. 60

3. A wire-coiling machine comprising, in combination, a frame, *A*, having a base portion, *B*, and standards *B'* *B*², a rotary longitudinally-reciprocating shaft, *C*, supported in the standards and carrying toward one 65 end a crank, *D*, and toward its opposite end a bed-plate, *E*, provided with a stud, *s*, and gage *q*, and with clamping mechanism comprising a guide-plate, *r*, and clamp *p* on one side and a spring-lever, *p'*, on its opposite side, a stop, *n*, to limit the rotation of the bed-plate in one direction, and a stop, *n'*, to limit its rotation in the opposite direction, substantially as described. 70

4. In a wire-coiling machine, the combination, with the frame, of a bed-plate, *E*, on a rotary shaft, *C*, and having clamping mechanism to hold the wire, and a stud, *s*, on one side, and a holder, *F*, having a shoulder, *o*, and an eye, *o'*, adjustable on and removable 80 from the stud *s*, substantially as described.

5. In a wire-coiling machine, the combination, with the frame, of a bed-plate, *E*, on a rotary shaft, *C*, and having clamping mechanism to hold the wire, a stud, *s*, and cam *s'* 85 on one side, and a holder, *F*, having a shoulder, *o*, and an eye, *o'*, adjustable on and removable from the stud *s*, substantially as described.

6. A wire-coiling machine comprising, in 90 combination, a frame, *A*, having a base portion, *B*, and standards *B'* *B*², a rotary longitudinally-reciprocating shaft, *C*, supported in the standards and carrying toward one end a crank, *D*, and toward its opposite end a bed-plate, *E*, provided with a stud, *s*, cam *s'*, and gage *q*, and with clamping mechanism comprising a guide-plate, *r*, and clamp *p* on the end of a shaft on one side of the bed-plate and a spring-lever, *p'*, on the other end of said 100 shaft on the opposite side of the bed-plate, a stop, *n*, to limit the rotation of the bed-plate in one direction, a stop, *n'*, to limit its rotation in the opposite direction, and holder *F*, having a shoulder, *o*, and an eye, *o'*, and adjustable on and removable from the stud *s*, 105 substantially as described.

ALVA OWEN.
